UNITED STATES PATENT OFFICE

DAVID B. MACKENZIE, OF MUSCATINE, IOWA

RELISHING MACHINE

Application filed September 9, 1929. Serial No. 391,354.

My invention relates to improvements in relishing machines, and it consists in the combinations, constructions, and arrangements herein described and claimed.

5 An object of my invention is to provide a relishing machine of the type in which sash rails move in a continuous line through the device and in which novel means is provided for relishing the tenon portions of the sash rails during the continuous movement of the latter.

10 A further object is to provide a relishing machine which may be disposed in operative relation with a sticking unit in such a manner that the rails ejected from the sticking unit are moved through the relishing machine and in which the necessity for special means for moving the rails through the relishing machine has been reduced to a minimum.

15 A further object is to provide a relishing machine in which means is provided whereby two tenons are relished in one operation, and in which novel means is provided whereby the sash rails are fed in a continuously moving line through the machine and effectively relished irrespective of the length of the rails.

20 A further object is to provide a relishing machine which may be disposed in operative relation with respect to a sticking unit and synchronized with the latter in such a manner that the number of operations necessary in finishing the rails is reduced to a minimum.

25 A further object is to provide a relishing machine in which novel means is provided for adjusting the mechanism for cutting the relish in a minimum amount of time and with a minimum amount of structure.

30 Other objects and advantages will appear in the following specification, and the novel features of the invention will be particularly pointed out in the appended claims.

35 My invention is illustrated in the accompanying drawings, forming part of this application, in which

Figure 1 is a front elevation of my device,

40 Figure 2 is an enlarged front elevation of a portion of the structure shown in Figure 1,

Figure 3 is a rear elevation of the structure shown in Figure 2,

Figure 4 is an end elevation of my device.

45 Figure 5 is an enlarged sectional detail view taken substantially along the line 5—5 of Figure 3,

Figure 6 is an enlarged sectional detail view taken substantially along the line 6—6 of Figure 1,

50 Figure 7 is a detail view of two pieces of stock finished by my device,

Figure 8 is a face view of the large cutter which I employ,

55 Figure 9 is a side elevation of the cutter shown in Figure 8,

Figure 10 is an enlarged detail view of a slide mechanism,

60 Figure 11 is a sectional view taken substantially along the line 11—11 of Figure 10, and

Figure 12 is a sectional view taken along the line 12—12 of Figure 3.

65 In carrying out my invention, I make use of upright supporting members 1 and 2 spaced apart as shown in Figures 1 and 4.

70 Channel members 3 are secured to the members 1 and 2 by means of bolts 4, see Figures 1 and 4. Supporting brace members 5 are also secured to the upright members 1 and 2 by means of bolts 6. The members so far defined are preferably cut from channel iron but may be of any other suitable material. Suitable cross brace members 7 may be secured to the upper ends of the upright members 1 and 2 as shown in Figures 1 and 4. The cross members 7 support longitudinal frame members 8. The members 8 may be bolted to the cross members 7 by means of bolts 9.

75 In Figure 1 I have shown the ends of the longitudinal frame members 8 as being connected with one end of a sticking unit 10. The members 8 are properly aligned with the sticking unit so that the stock which is ejected from the sticking unit will be passed onto a table 11 carried by the members 8. The table terminates at 12, see Figure 1. A companion table 13 is mounted upon the opposite ends of the members 8 and terminates 80

85

80

85

90

at 14. Pairs of brackets 15 and 16 are mounted upon suitable channel members 17 and 18, respectively. The brackets are spaced apart as shown in Figure 4. A guide block 19 is disposed between the upper ends of each pair of brackets, see Figures 4 and 2. The blocks are provided with a V-shaped groove 20. Each block is provided with an elongated opening 21, see Figure 2, for receiving 10 a bolt 22. A suitable bolt 23, see Figure 4, is provided in conjunction with each of the bolts 22 whereby the upper ends of each pair of brackets may be firmly secured together and rigidly supported by means of one of 15 the members 8. The lower ends of each pair of brackets are provided with flange portions 24, see Figure 1, whereby the bases of the brackets may be rigidly secured to the channels 17 and 18 by means of bolts 25. A 20 wheel 26 having a V-shaped groove 27 is disposed between each pair of brackets 15 and 16.

A movable carriage 28 is disposed between the brackets 15 and the brackets 16. The 25 carriage is provided with tapered edges 29 and 30 which are guided by the V-shaped grooves 20 and 27, respectively. The carriage 28 is provided with an upper bearing portion 31 and a lower bearing portion 32, see 30 Figures 1, 3, and 5. Side spindles 33 and a center spindle 34 are mounted within the bearing portions 31 and 32. The spindles are arranged for reciprocatory movement with respect to their longitudinal axes. The 35 lower ends of the spindles are provided with bearing members 34' having splined relation with the spindles. Each spindle is provided with such a splined construction, see Figure 1. Each of the spindles 33 is provided with 40 a gear 35. These gears are disposed in mesh with a gear 36 associated with the central spindle. A bevel gear 37 is connected with the gear 36 and is disposed in mesh with a sliding bevel gear 38. The gears 35 and 36 45 may be rotated through the medium of the bevel gears 37 and 38. Rotation of the latter will cause the bearing members 34' which have splined relation with the spindles 33 and 34 to turn the spindles. Splined constructions such as that used in connection 50 with the spindles 33 and 34 are well known in the art and therefore require no detailed description.

The spindles 33 are provided with bits 39 55 and the spindle 34 is provided with a relatively large cutter 40, see Figure 3. The cutter 40 comprises a head portion 41, see Figures 8 and 9, having cutting blades 42 secured thereto by means of screws or bolts 60 43. The blades are provided with spirally arranged cutting edges 44. In Figure 7 I have shown a pair of sash rails 45 and 46 having tenon portions 47. The bits 39 cut recesses 48 in the ends of the sash rails. The 65 cutter 40 cooperates with the bits 39 for rel-

ishing the sash rails as indicated at 49. The cutting edges of the cutter 40 are so designed that a smooth cut is made and the tendency for the tenons to split is reduced to a minimum. The manner in which the cutters are moved into engagement with the tenons 47 will be defined later.

In referring to Figures 1 and 2, it will be noted that the cutting edges of the cutter 40 and the bits 39 are slightly below the upper surface of the table 11. Figure 3 shows the positions of the cutter and the bits with respect to the table, while the former are in their elevated position for cutting the relish. A pair of guide members 50 is mounted upon the portions 31 and 32, see Figures 1 and 2. The guide members are arranged to movably support a spacer comprising portions 51 rigidly connected together by means of cross members 52 and 53. It will be noted that the upper ends of the portions 51 project slightly above the upper face of the table 11. The purpose of this construction will be defined later in connection with the explanation of the operation of the mechanism. A lever 54 is pivotally connected at 55 with one of the portions 50. The lever is provided with a cam portion 56. The opposite end of the lever is operatively connected with the cross member 53, see Figures 1, 2, and 5. A bracket 57 is secured to the portion 32, see Figure 5, and is arranged to support one end of a spring 58 which bears against the under edge of the cross member 53. The cross member 53 is provided with a guide rod 59 which passes through an opening in the bracket 57. The spring 58 tends to hold the spacing device or portions 51 in their normal position shown in Figures 1 and 2. When the carriage 28 is moved from the full line position to the dotted line position shown in Figure 2, the cam portion 56 engages a roller 60 carried by one of the brackets 16. At this time the spacer is moved downwardly for positioning the ends of the portions 51 below the upper surface of the table 11. It will also be noted in referring to Figure 2 that the cutter 40 and the bits 39 are in their elevated position when the carriage is in its shifted position.

A movable frame 61 comprising end portions 62 and 63 and cross members 64 and 65 is mounted upon a supporting frame 66 comprising upright bracket members 67 and a cross member 68. The bracket portions 67 are mounted upon the table 11 and secured thereto by means of bolts 69, see Figure 4. The frame 61 is movably connected with respect to the supporting frame 66 through the medium of a screw 70, see Figure 1. Rotation of the screw 70 will cause an upward or downward movement of the frame 61, depending upon the direction of rotation of the screw 70.

Referring now to Figures 2 and 6, it will be noted that the cross member 65 associated

with the frame 61 is provided with a recess 71 within which a slide 72 and a companion slide 73 are disposed. The recess is provided with tapered walls for retaining the slide members 72 and 73, as shown in Figure 6. The slide 72 is provided with a bracket 74. The bracket is secured to the slide by means of bolts or screws 75. A lever 76 having a slot 77 is mounted upon the connecting portion 78 between the horizontal portions 64 and 65. The slot 77 permits longitudinal movement of the lever 76. A retaining bolt 79 holds the lever upon the portion 78. The lever is connected with the bracket 74 through the medium of a link 80. The lower end of the lever is operatively connected with a companion slide 73 at 81. Movement of the slide 72 will cause a movement of the companion slide 73 through the medium of the bracket 74, the link 80, and the lever 76. The slide 72 and the companion slide 73 are shown in their normal positions in Figure 2. A guide member 82 is secured to the frame 61, see Figures 2 and 4, by means of bolts 83, see also Figure 6. Companion guide members 84 are secured to the tables 11 and 13 and are disposed in alignment with the guide 82.

The rails which are to be relished are ejected from the sticking unit which I have indicated generally at 10 upon the table 11 and are held snugly against the guides 82 and 84 by reason of spring members 85 associated with posts 86 carried by brackets 87. The sash rails are ejected from the sticking unit onto the table 11 in a continuous line. The tenons are bored and relished while passing over the tables 11 and 13 in a continuous line. The tenon on one end of a sash rail abuts against the tenon of another rail. In Figure 2 I have shown the tenons of two sash rails at 88 and 89. In Figure 7 I have indicated the sash rails as being provided with shoulders 90. A shoulder is provided upon each side of the tenon. When the stock is ejected from the sticking unit, each piece is passed onto the table 11 and moved in the direction of the relishing unit.

Referring now to Figure 2, it will be seen that the shoulder 90 associated with a piece of stock indicated at 91 will engage a push dog 92 mounted upon a plate 93 which is fixed to the slide 72. The push dog is mounted for movement about a bolt or other suitable supporting member 94. The rail is held against the guides 82 and 84 by reason of the spring members 85, see Figures 4 and 6. When the shoulder 90 associated with the rail 91 has engaged the push dog 92, the sliding bar 72 and the companion bar 73 will be caused to move in the direction of an arrow 95, see Figure 2. The movement of the slide 72 will cause the lever 76 to be moved from the full line position to the dotted line position. At this time a release dog 96 which is in engagement with the push dog 92 will en-

gage a cam surface 97 for moving the dog out of engagement with the push dog. Thus the sash rail 91 is pushed down through the machine and the slide 72 and the companion slide 73 are moved back to their normal position by means of a spring 98.

Let us assume that one sash rail has already passed the push dog 92 and that there is a continuous line of sash rails passing through the unit. The end of one of the tenons associated with the rail 91 will engage the end of a tenon on the end of a rail in advance of the rail 91 at X. When the tenons of the two rails reach the point indicated at X, the push dog 92 is in engagement with one of the shoulders on the rail 91 and a dog 99 is in engagement with the shoulder 90 associated with the rail in advance of the rail 91. The dog 99 is movably connected with the companion slide 73. As the rail 91 continues its movement in the direction of the arrow 95, the dog 92 will be moved from the full line position to the dotted line position and the dog 99 will be also moved from the full line position to the dotted line position. At this time the shoulder 90 associated with the rail in advance of the rail 91 will be positioned in a plane indicated at W in Figure 2. The upper ends of the members 51 are depressed and held in a plane on a level with the upper surface of the table 11. In other words, the ends of the spacer bear against the underneath edge of the sash rail passing over the particular point at which the members 51 are positioned. Now going back to the full line position of the parts shown in Figure 2 continued movement of the sash rails through the relishing machine will bring the shoulder 90 associated with the rail 91 in engagement with a stop portion 100 associated with one of the members 51, see Figures 5 and 8, and the stop portion 100 associated with the other of the members 51 will engage the shoulder of the advance rail as indicated at W in Figure 2.

As the rail 91 is pushed through the machine, the carriage 28 will be moved from the full line position shown in Figure 2 to the dotted line position. The spacer holds the rails apart at a predetermined distance. During the movement of the carriage from its full line position to its dotted line position, the cutter 40 and the bits 39 will have moved from the full line position to the dotted line position. Such movement of the cutter and the bits provides the grooved and relished stock as shown in Figure 7. The means for elevating the cutter and the bits will be defined later.

When the carriage is in the dotted line position, the cam portion 56 is riding upon the wheel 60. Movement of the lever 54 upon which the cam portion 56 is provided causes the spacer to be depressed for moving the upper ends of the members 51 below the

underneath side of the rail 91. A slight movement of the rail will bring it into position for holding the spacer in its depressed position until a pair of rails has again been spaced apart for permitting the spacer to engage the shoulders as above described.

The shoulder of one rail in engaging one side of the spacer moves the carriage, and the other side, in engaging the shoulder of 10 the other rail in spaced relation with the first-mentioned rail during the relishing process, will push the latter. Let us now refer to Figures 2 and 3. Figure 2 shows one side of the device and Figure 3 shows the opposite side. 15 A yoke 101 is associated with the spindles 33 and 34. The spindles are provided with collars 102 and 103, see also Figure 5. The yoke 101 is provided with a wheel 104 which is arranged to ride upon a slide 105. The slide is 20 mounted for movement about an axis comprising a bolt or other suitable supporting means indicated at 106. The slide may be moved about the axis 106, as will be defined later. The wheel 104 engages the slide when 25 the wheel is in the dotted line position 107. Since the wheel is fixed with respect to the yoke 101, it will be seen that the spindles 33 and 34 will be lifted a distance equal to the vertical distance between the position 107 and 30 the position 108 shown in Figure 3. This distance is equal to the amount that the tenons are relished. Inclination of the slide may be changed for varying the distance that the cutting mechanism is lifted. 35 In Figure 10 I have shown an enlarged detail view of the slide. The wheel 104 is shown at the beginning of its lifting action. In Figure 3 the wheel has completed its lifting action. The carriage in Figure 3 is 40 shown in a shifted position. In fact, the carriage has substantially completed its shifted movement. The slide 105 is associated with a bracket 109 which moves with the slide when the latter is dropped. In referring to Figure 3, it will be noted that the wheel has engaged a cam 110, and that the cam is provided with a cam surface 111 arranged to move the wheel downwardly as the carriage moves in the direction of an arrow 112. The 45 bracket 109 is provided with a spring 113 which normally holds the slide in the inclined position shown in Figures 3 and 10. The spring 113 is provided for moving the bracket from its dotted line position to the full line position shown in Figure 3 when the carriage moves back to its normal position. 50

The wheel 104 is arranged to run upon the upper edge of the bracket 109, as shown in Figure 3. As the carriage continues in its movement in the direction of the arrow 112, the cam 110 will tend to move the slide downwardly about its pivot 106. The slide is locked in its inclined position during the time that the wheel is moving from the position shown at 107 to the position shown at 108.

When the wheel reaches its elevated position as shown in Figure 3, an arm 114 which is fixed to the carriage engages a collar 115 carried by a trip bar 116. The trip bar is provided with a lever 117 provided with a projection 118 which is normally positioned for engaging a pin 119 carried by the bracket, whereby the slide is supported in its inclined position. The lever is pivotally mounted at 120 upon a stationary frame member 121. A slight movement of the carriage after the arm 114 has engaged the collar 115 will move the lever from its full line position to its dotted line position, at which time the projection 118 will be moved from underneath the pin 119. 70

Continued movement of the carriage at this time will cause the wheel 104 to be moved downwardly by reason of the cam surface 111. Such movement of the wheel will of course lower the cutter and the bits which have been lifted upwardly by reason of the yoke associated with the wheel. The weight of the yoke, the cutter and the bits, and their associated mechanism will ordinarily move the slide and the bracket to the dotted line position shown in Figure 3. The cam provides means whereby the return of the cutter and the bits is made certain. The cam may be adjusted by means of a screw bar 122. 80

After the slide has been returned to its normal position, the upper edge of the slide is aligned in a plane occupied by the bracket 109 shown in Figure 3. As soon as the wheel reaches the position shown in Figure 3; that is, when the wheel is positioned above the pivot 106, the spring 113 will move the bracket from the dotted line position to the full line position. When the carriage returns to its normal position, the arm 114 engages a collar 123 for moving the lever 117 from its dotted line position to the full line position, at which time the projection 118 will be positioned underneath the pin 119 for supporting the slide in its elevated position. In Figure 2 I have shown the sliding bevel gear 38 as being operatively connected with a bracket 124. The gear 38 has splined relation with respect to a drive shaft 125 which is supported at its ends by means of bearings 126 and 127. The shaft may be operatively connected with a power shaft 128 which may be operatively connected with any suitable source of power, not shown. 100

Referring now to Figure 10, it will be noted that I have provided a bolt 129 which has a swivel connection at 130 with a member 131 associated with the slide 105. The bracket 109 is provided with a pin 132 having a threaded opening for receiving the threaded portion of the bolt 129. The bolt is provided with a head 133 which permits the bolt to be turned manually for adjusting the inclination of the slide with respect to the bracket. The bracket is provided with a projecting portion 134 which is slotted at 105 110 115 120 125 130

135 for permitting the member 131 to be slidably mounted. Thus it will be seen that a slight rotation of the head 133 will change the inclination of the slide, depending of course upon the direction in which the bolt is turned.

From the foregoing description of the various parts of the device, the operation thereof may be readily understood. The sash rails are ejected from the sticking unit onto the table 11 and moved through the relishing machine in a continuous line. The sash rails are relished during the movement of the rails through the machine. In Figure 2 I have shown the normal position of the carriage 28 and the sliding bars 72 and 73. Let us assume that a continuous line of sash rails is passing through the machine. A shoulder of one rail will engage the push dog 92 which tends to assume an upright position by reason of a spring 136. When the push dog is in its full line position, the dog is rigidly supported by means of the release dog 96 which is held in engagement with the push dog by reason of a spring 137. When the carriage is in its normal position, the dog 99 will be in engagement with the shoulder associated with the rail in advance of the rail 91. At this time, the spacer is in its depressed position. As the rail 91 continues its movement through the machine, the sliding bars 72 and 73 will be moved, at which time the sliding bar 73 will be moved faster than the bar 72, whereby the dog 92 will be moved from its full line position to the dotted line position, and the dog 99 from its full line position to the dotted line position.

When the dogs are thus positioned, the spacer will be moved upwardly sufficiently far, whereby one of the shoulders associated with the rail 91 will engage one of the members 51 and thereby cause a movement of the carriage 28. Almost simultaneously the other member 51 associated with the spacer will engage the shoulder associated with the rail in advance of the rail 91, whereby the two rails are held in spaced relation and at the same time move in unison with the carriage 28. The movement of the carriage at this time is from the full line position shown in Figure 2 to its dotted line position. During the movement of the carriage, the wheel 104 associated with the yoke 101 will ride upon the slide 105 for elevating the cutter and bits from their lower position shown in Figure 2 to the elevated position shown in Figure 3. Such movement of the cutter and bits will complete the relishing and grooving of the tenons associated with the spacer. When the carriage is in its shifted position, the lever 54 will engage the wheel 60 for depressing the spacer and the cutter and bits will be moved downwardly for permitting

the sash rails to move without being obstructed.

In Figure 2 I have shown the carriage 28 as being provided with a pair of guide members 138 for cooperating with the tables 11 and 13 in supporting the rails. The guide members 138 of course move with the carriage. In referring to Figure 1, it will be noted that the movable frame 61 may be adjusted by reason of the screw 70 for accommodating rails of different widths. In view of the fact that the relishing mechanism is actuated by certain rails passing through the machine at any given time, it will be seen that I have eliminated the necessity of adjusting the machine to accommodate various lengths of rails. In the present device, the rails may be mixed as to length without any necessity of adjusting the machine.

I claim:

1. In a device for relishing rails, the combination of a supporting frame, a carriage carried by said frame and slidably with respect thereto, means carried by said frame and adapted for engaging continuously moving rails for positioning the abutting ends of said rails in spaced-apart relation, rail-engaging means connected with said carriage and adapted for engaging said spaced-apart rails for moving said carriage, cutting elements carried by said carriage, and means for moving said cutting elements transversely with respect to said carriage for relishing the rails.

2. In a device for relishing rails, the combination of a supporting frame, a carriage carried by said frame and slidably with respect thereto, means carried by said frame and adapted for engaging continuously moving rails for positioning the abutting ends of said rails in spaced-apart relation, rail-engaging means connected with said carriage and adapted for engaging said spaced-apart rails for moving said carriage at a uniform rate of speed with said rails, cutting elements carried by the carriage, and means operatively connected with said carriage for moving said cutting elements transversely with respect to said carriage when said carriage and rails are in motion.

3. In a device for relishing rails, the combination of a supporting frame, a carriage carried by said frame and slidably with respect thereto, means carried by said frame and adapted for engaging continuously moving rails for positioning the abutting ends of said rails in spaced-apart relation, rail-engaging means connected with said carriage and adapted for engaging said spaced-apart rails subsequent to the spacing thereof for moving said carriage at a uniform rate of speed with said rails, cutting elements carried by the carriage, means for moving said cutting elements transversely with respect to said carriage when said carriage and rails

are in motion for relishing the rails, and means for returning said cutting elements to their normal positions relative to the carriage subsequent to the relishing of said rails.

- 5 4. In a device for relishing rails, the combination of a supporting frame, a carriage carried by said frame and slideable with respect thereto, means carried by said frame and adapted for engaging continuously moving rails for positioning the abutting ends of said rails in spaced-apart relation, rail-engaging means connected with said carriage and adapted for engaging said spaced-apart rails subsequent to the spacing thereof for 10 moving said carriage at a uniform rate of speed with said rails, cutting elements carried by the carriage, means for moving said cutting elements transversely with respect to said carriage when said carriage and rails 15 are in motion for relishing the rails, means for returning said cutting elements to their normal positions relative to the carriage subsequent to the relishing of said rails, and spring means for returning said cutting elements and carriage to their normal positions 20 relative to the supporting frame.

- 25 5. In a device of the type described a supporting frame, means carried by said frame and adapted for engaging continuously moving rails whereby the abutting ends of said rails may be disposed in spaced-apart positions, said means comprising a pair of slideable members, a catch member mounted on each of the slideable members and adapted 30 for engaging a rail, and lever means operatively connected with said slideable members whereby said catch members may be moved at a different rate of speed when one of said slideable members is actuated.

35 40 Signed at Muscatine, Ia., in the county of Muscatine and State of Iowa, this 28th day of August A. D. 1929.

DAVID B. MACKENZIE.
